(57) **CLAIM**

The ornamental design for a shower door and panel, as shown and described.

DESCRIPTION

FIG. 1 is a perspective view of a shower door and panel. FIG. 2 is a front elevation view of the shower door and panel.

FIG. 3 is a rear elevation view of the shower door and panel.

FIG. 4 is a left-side elevation of the shower door and panel.

FIG. 5 is a right-side elevation of the shower door and panel.

FIG. 6 is a top plan view of the shower door and panel; and, FIG. 7 is a bottom plan of the shower door and panel.

In the drawings, the broken lines shown in FIGS. 1-7 indicate portions of the article not claimed and form no part of the claimed design.
